UNITED STATES PATENT OFFICE.

THOMAS ABBOTT, OF NEW YORK, N. Y.

BAGGAGE-CHECK.

SPECIFICATION forming part of Letters Patent No. 268,591, dated December 5, 1882.

Application filed May 3, 1881. (Model.)

To all whom it may concern:

Be it known that I, THOMAS ABBOTT, a resident of the city, county, and State of New York, have invented an Improved Baggage-Check Holder, of which the following is a specification.

My invention relates to baggage-checks, adapted to checking back and forth over different lines of railroads to any given station and return, as indicated upon the check and holder.

The details of construction are as follows:

In the accompanying drawings, Figure 1 represents the original plate for a baggage-check holder as first stamped out of the metal. Fig. 2 shows the face of the holder when completed, with the strap attached. Fig. 3 shows the back of the holder when completed, with part of the back turned over, with strap attached. Fig. 4 represents the check or card before being inserted in the holder. Fig. 5 shows the check which is given to the passenger.

The metal plate is about five inches in length and about one and three-quarters inch in width, the face-plate, as shown in Fig. 1, F F, being about one-quarter of an inch less in width than the back plate, G G. The back plate is bent up about one-eighth of an inch at each edge B B B B, and bent over reversely from the face 30 at C C, as seen at H, in Fig. 3. The face-plate F F, which is one-quarter inch less in width than the back plate, G G, is bent over at A A, and fits into and between the bent-up edges of the back plate, so as to make an inclosed space, 35 as seen at D. The face-plate has three distinct openings, J J J, each opening about three-sixteenths of an inch from each edge of face. The first or upper one is about one-quarter inch in width, and has the word "from" stamped in 40 the metal above it to show the starting place. The second or middle one is about five-eighths of an inch in width, and has the word "via" stamped in the metal above it to designate the route. The third or lower one is about one-quarter inch in width, and has the word "to" stamped in the metal above it to show the 45 destination of the baggage or other article to which the holder is attached.

At D is the inclosed space between the face 50 and the back of the holder, into which is inserted the check or card, Fig. 4, which is made

preferably of thick light-colored paper, on which is printed or written the starting-point, the route, and the destination, and which, although inclosed, secured and protected when 55 in the holder, can be seen and read through the openings J J J. Said check or card when so inserted is a part of said holder, but detachable therefrom, and the reverse side or back of the check is the same as the face, Fig. 60 4, the lettering omitted.

On the back of the holder, Fig. 3, is stamped in the metal the directions for use, which can be seen and read, as the strap does not cover (and this is one of the features of my device) 65 the lettering, in the following words: "Reverse the card in this holder and use in return to a station on the [for example] N. Y., L. E. & W. R. R. only. If this holder is not required for use in 30 days, return to the general baggage 70 office [for example] N. Y., L. E. & W. R. R. 100 A." The check, Fig. 5, which is to be given to the passenger consists of a metal plate about two inches in length and about one and three-quarters inch in width. On the face of 75 it is stamped in the metal the directions in the following words: "This check to be given a passenger who holds a ticket per route as card in holder to or from a station on the [for example] N. Y., L. E. & W. R. R. only 100 A." 80 The back of this check, Fig. 5, is plain.

The strap K is about ten inches in length and about five-eighths of an inch in width, with a slit about three and one-half inches long cut into it to pass the holder through for the purpose of attaching it to the article to be transported. The end of the strap is secured to the holder under H, Fig. 3, and is about one inch in width, to keep it from being drawn through the hole. The holes for the strap to pass through 90 are shown at X, Figs. 2, 3, 4, and 5. The strap, when secured under H, passes through holes X, Fig. 3, thence through hole X, Fig. 4, when the card shown in Fig. 4 is inserted; thence through hole X, Fig. 5, when the check shown 95 in Fig. 5 is not in use.

By means of the construction of the holder, as above described, a stout receptacle for the card is provided, which, with the strap K, passed through the slot of the card, securely 100 protects the card from injury and will not bend, so as to jam the card in the holder and render

it difficult of removal. The operation of my device is as follows: The card is placed in the holder, with the strap passed through the card, and the destination, &c., is very apparent through the slots. By means of the lip L the check may be readily inserted in the holder, as the lip serves as a guide. The check is thereby securely incased in the holder, and there is no liability of loss of the baggage or its going astray by reason of the plain and fully-visible directions, which may be read at a glance. The handling of my device is facilitated, as it simply requires the removal of the strap from the check. Upon reaching its destination the check is removed from the holder, after withdrawing the strap, and replaced in the holder, and either the station whence it came will be manifest through the slots, or the general baggage-office of the railroad company to which return is requested, will appear on the reverse side. And, further, being, as shown,

secured by the strap, the holder and check will be used the more readily in return to the first starting-point or other station on the railroad issuing the check. ²⁵

Having thus described my invention, what I claim is—

A baggage-check holder formed from a single piece of metal, with a slotted side, having a lip to guide the check or card readily into the holder, and a plain side, with flanges bent over, so as to form a rigid and strong holder for the protection of the check or card, with directions as to the route and destination appearing on one side of the holder through the slots, the other side of the holder bearing directions to a place of return, and having also a strap adjacent to its mouth, substantially as set forth. ³⁰ ³⁵

THOMAS ABBOTT.
